[57] CLAIM

The ornamental design for an electrical connector housing, as shown and described.

DESCRIPTION

FIG. 1 is a top plan view of an electrical connector housing showing our new design;

FIG. 2 is a front elevational view thereof;

FIG. 3 is a bottom plan view thereof;

FIG. 4 is a left side elevational view thereof;

FIG. 5 is a right side elevational view thereof;

FIG. 6 is a rear elevational view thereof;

FIG. 7 is a perspective view thereof, looking from front side;

FIG. 8 is a perspective view thereof, looking from rear side;

FIG. 9 is a perspective view thereof, looking from the rear side, where the terminal holder is removed for the purpose of a complete disclosure; and

FIG. 10 is a perspective view thereof, showing the housing aligned for coupling with corresponding connector housing. The broken line showing of the corresponding housing is included for the illustration of environmental elements only and forms no part of the claimed design.
